UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK C. STEVENS, OF ATTICA, NEW YORK.

TELEPHONE-EXCHANGE SYSTEM.

1,091,193.

Specification of Letters Patent. Patented Mar. 24, 1914.

Application filed January 19, 1906, Serial No. 296,853. Renewed December 31, 1910. Serial No. 600,276.

To all whom it may concern:

Be it known that I, EDWARD E. CLEMENT, a citizen of the United States, residing at Washington, in the District of Columbia, 5 have invented a certain new and useful Improvement in Telephone-Exchange Systems, of which the following is a specification, reference being had therein to the accompanying drawings.

10 My invention relates to telephone exchange systems, and has for its object the provision of means whereby incoming calls from subscribers' stations or other stations may be automatically apportioned among 15 the idle portions of the connective apparatus.

This invention is applicable to, and I shall describe it in connection with exchanges equipped both with manual and with automatic switching devices for interconnecting 20 lines. It is capable of application in a number of ways, and may be embodied in various forms, some of which I shall indicate, but I have selected for specific description herein what I consider to be the best form devised 25 up to this time.

The theory upon which my invention is based is this: In all telephone exchanges a certain proportion of the apparatus is idle most of the time, and all of the apparatus is 30 idle some of the time. In a manual exchange, wherein double cords terminating in pairs of plugs are employed for purposes of interconnecting the lines, the number of pairs of such cords and plugs required in an average

35 city exchange is theoretically equal to about ten per cent. of the total number of lines to be served. In practice, this percentage is somewhat increased, because some of the cords are almost always out of service, and 40 short periods are apt to occur in which the number of calls rises abnormally. In some exchanges the percentage of connecting cords is as high as 17, but this is because the load is apt to jump unequally on different

45 parts of the board. That is to say, that one operator will receive a great many calls from her particular group of subscribers, when others are comparatively idle.

One purpose of my present invention is 50 to correct this unequal distribution of the calls, by causing the first line calling to be connected automatically to the first idle cord or other connective circuit, the second line calling to the second idle connective circuit, and so on.

In automatic exchanges, that is those in which machines at the central office are controlled from the subscribers' stations to interconnect the lines, the trouble I have mentioned of unequal distribution has not 60 made itself so apparent, for the reason that in most if not all of the large exchanges now in actual operation, each line has an individual switch by which it can be placed in connection with any one of a considerable 65 number of others, through which it is finally connected to the line wanted. Such an arrangement, however, is expensive, for there must perforce be a number of the first selector switches as they are called, which is 70 70 equal to the number of lines, and from ten to thirty per cent. of other or auxiliary switches according to the size of the exchange. In an exchange of 1,000 lines, the number of switches is thus 110 per cent. of 75 the number of lines; in a 10,000 line exchange it is 120 per cent. Since most city exchanges have between 1 and 10,000 subscribers, it is customary to figure on 1.2 switches per line, and as compared with 80 the manual switchboards, the inherent economies in the automatic system, which are due to their low operation and maintenance charges, do not begin to make themselves apparent until after the 4 or 5,000 line 85 size is reached. Manual multiple-boards accommodating that many lines begin to get very expensive by comparison, especially in operation.

My present invention enables me to economize switches in an automatic exchange by providing only a limited percentage of first selector switches, and distributing the incoming calls among these, the first line to call being automatically connected to the 90 first idle switch, the second to the next idle switch, &c.

Since I used the same character of line-circuit in my automatic systems and manual systems, that is to say the same plain metallic circuit, the apparatus which I employ to effect the distribution in both manual and automatic systems is the same. It consists merely of relays. It has heretofore been proposed to use moving switches, which 105 have been called "starters" and "finders" by some persons, and which I have called "primary selectors," for the purpose of picking out a calling line in a group, and connecting it to a switch whereby further connec- 110

tions might be made. Such devices, however, have the inherent uncertainty and liability to derangement which are inseparable from all moving pieces of apparatus, especially of an electrical nature, where they are governed and moved by electromagnets. According to my present invention there can be no uncertainty in operation, because I use simple positive acting relays, which work without margin on current or no current in their circuits; and there is very little liability of derangement of these relays, because they are mounted and housed in a manner now well understood in the art, that is to say on iron racks and in dust-proof cases.

Briefly stated, the invention consists in dividing the lines into groups, in which they may be distributed through an intermediate frame for answering purposes, as is now customary with manual, multiple switchboards, assigning to each group a fixed percentage of trunks or cord-circuits, as the case may be, and providing a set of connecting relays for each trunk whereby it may be connected if the proper combination of relays be energized to any line in the group to which it is assigned.

Each connective circuit has a bridged battery and a pair of bridged controlling relays, and local circuits are provided such that when any line calls and is connected, it will control the trunk circuits. Only one set of relays will be energized, that one which corresponds to the first idle connective circuit, because I arrange the controlling relays of the connective circuits so that as each becomes busy it will disable all of its own selective relays except the one through which it is connected, at the same time connecting and rendering active the relays of the next trunk or connective circuit in order.

Where the invention is used with a manual system, the connective circuits to which I refer may be ordinary single cord-circuits terminating in plugs or jacks, and each having an associated signal, whereby an operator will be apprised of the call when it comes. Where the invention is employed with automatic switches, the connective circuits are trunks, if I may so call them, leading to first selector switches, the number of the latter being thus reduced to a number less than the number of lines.

The best embodiment of the invention now known to me requires two relays per line, or two hundred relays for each one hundred lines. One-half of these relays are what I shall term multiple contact relays, and the other half what I shall term single-contact relays. The multiple-contact relays consist each of an electromagnet having a movable armature and either ten or twelve double pairs of contact springs with platinum

points. Such a relay takes the place of ten single relays, and receives ten lines. Each line is connected to the same contact in ten of these relays, in multiple. The single relays, on the other hand, are of the ordinary type commonly used in telephone exchanges, each comprising a single electromagnet with one or more double pairs of contact springs.

The multiple-contact relays I shall refer to also as the tens relays, and the single-contact relays as the units relays. These relays are mounted in banks, ten of each kind to a bank and one bank to each trunk or connective circuit. The circuits of the tens and units relays are so arranged that when a given line calls it closes the circuit of all the tens relays corresponding to the tens digit of its line, and all the units relays corresponding to the units digit of its line. Only those relays are active which lie in the bank appertaining to the first idle trunk or connective circuit. Assuming No. 34 to be the number of the calling line in the group, the third tens relay and the 4th units relay will pull up simultaneously, and their local circuits being combined by this joint action connect the line with the trunk or cord-circuit to which the bank belongs. All other relays in the bank are instantly disabled, the operative relays are themselves locked as long as the calling line remains in use, and the relays of the next idle connective circuit become active.

It will be observed that in this system the calling line is selectively connected to an idle trunk through the mere closure of the calling subscriber's line circuit. I am aware that systems have been proposed in which single relays are actuated by means of grounded circuits controlled by keys at the subscribers' substations. Such systems however, are inefficient and commercially impracticable.

The selected form of my invention to which I have referred is illustrated in the accompanying drawings, in which—

Figures 1, 2, 3, 4, 5 and 6 form parts of a complete diagram from calling subscribers' stations through the connective apparatus at the central office. Of these, Fig. 1 shows three subscribers' stations and the line-circuits leading to central. Figs. 2 and 3 show a terminal set of two tens relays for each of three trunks. Fig. 4 shows the units relays for three trunks. Fig. 5 shows the bridging relays for the said trunks, the battery connections thereof, and the solenoid or controlling relays. Fig. 6 shows a selector switch and connector switch which are worked from the subscribers' stations through the intermediation of the relays in Fig. 5. Fig. 7 is a separate diagram showing the relation between the tens relays and the units relays of a single trunk. Figs. 8 and 9 are a side view with parts in section,

and a top plan view, respectively, of a ten point relay such as shown in Figs. 2 and 3. Fig. 10 is a face view and shows a type of automatic switch which may be employed in the circuits shown in Fig. 6. Fig. 11 is a section on the line $x-x$ of Fig. 10. Fig. 12 is a schematic diagram showing the method of primary distribution.

Before proceeding to the circuits, wherein the invention in the present case resides, it will be advisable to obtain a clear understanding of the pieces of apparatus which I employ, and which are shown in Figs. 8 to 11, inclusive. I do not give any special illustration of a single point or ordinary relay, for the reason that every one skilled in the art is so familiar with these devices as to render it unnecessary. That portion of my system which is illustrated in Figs. 2, 3 and 4 constitutes what I have termed the primary selector or answering portion of the system. In this, as already set forth, appear a number of ten point relays and a number of single point or ordinary relays. These latter may be of any suitable type. The only special feature required is that of double winding, which, as I shall point out hereinafter, can be dispensed with if some other means be provided for locking the relays when energized. The apparatus at the subscribers' stations also forms no part in itself of my present invention, except as it coacts with the apparatus and circuits at the central office. I contemplate using an ordinary common battery telephone outfit the same as those employed in standard manual switchboard systems, and with these subscribers' senders or signal transmitters shown in one instance in Fig. 1 as a key, and in the other instance as a hand-wheel with projecting pins passing over and under spring contacts. Referring then to Figs. 8 and 9, I will briefly describe the ten point relay, N. This comprises an iron back yoke, n , a pair of magnets, n' , mounted thereon, an armature, n^2 , extending across the front end thereof, and a set of contact springs, n^3 , n^4 , n^5 , n^6 , overlying the upper bell-crank extension of the armature, so as to be worked thereby. There are eleven sets of these springs, all secured at the rear end of the relay upon the return member, n^7 , of the back yoke. The front ends or pole pieces of the cores of the electro-magnets, n' , receive the front yoke, n^8 , of non-magnetic material, such as brass, this also having an upper return portion, n^9 , overlying the magnet windings, and alined with the return portion, n^7 , of the back yoke, n . Upon this return portion, n^9 , of the front yoke the upper bell-crank arm, n^{12} , of the armature, n^2 , lies flat under normal conditions. Cut from end to end of this upper bell-crank portion, n^{12} , are two grooves in which rest the insulating studs of the

spring sets. The function of these slots with the studs resting in them is to retain the armature in place. At their front ends the springs are separated by shouldered studs, the lowermost stud of each pair resting upon the armature, carrying the lower spring of its pair, n^6 , on its shoulder, and the upper spring, n^5 , on its head, its stem passing through a hole in the spring, n^6 , while the uppermost stud of each pair rests upon the spring, n^5 , supports the spring, n^4 , upon its shoulder, and carries the spring, n^3 , on its head, its stem passing through a hole in the spring, n^4 . The actuating studs affect only the springs, n^4 , n^6 , of each set, 75 these constituting the movable springs, while the others, n^3 , n^5 , are fixed. Each actuating stud carries the spring, n^6 , on its shoulder, and the spring, n^4 , on its head, its stem passing through holes in the springs, 85 n^5 , n^6 . The entire relay is secured to an insulating back block, n^{10} , by means of the bolts, n^{11} , constituting extensions of the cores and threaded to receive lock-nuts. The rear ends of the contact springs extend out through openings made in this back block, and an inclosing shell or casing, n^{13} , is fitted to the block, with which it forms a tight joint all around the edge. This shell is secured in place by means of 95 the stud, n^{14} , threaded to receive the nuts, n^{15} . As the armature, n^2 , is attracted, the springs, n^4 , n^6 , are lifted by the actuating stud, until their outer points make contact with the corresponding points of the 100 springs, n^3 , n^5 , in each set. Ten of these sets are line-contacts, and the eleventh is for locking purposes, as will sufficiently appear from the description of the circuits.

Referring now to Figs. 10 and 11, I have 105 therein shown a piece of apparatus which I do not present as a part of my invention, nor as an example of finished design in an automatic switch, but which is typical of the class of switches commonly known 110 as "Strowger" or "automatic electric" switches. As I have previously pointed out, my present invention may be practised with various connecting means, but in order to render this description complete and coherent, I include this form of switch, and its circuits.

As illustrated in Figs. 10 and 11, the switch is designated in toto by the letter S, and represents a selector switch, that is one 120 of the intermediate switch units to transfer a connection from the calling line to an idle trunk and switch in the desired thousands or hundreds group. It has a frame, s , provided with two posts, s' , extending downwardly to support the contact-banks, s^2 , s^3 , which as shown in Fig. 11 are arranged in a cylindrical figure around the central spindle s^4 . There are ten rows in each contact-bank, with ten pairs of contacts in each row 130

of the bank, s^2 , and ten single contacts in each row of the bank, s^3 . The contacts are radial strips of brass or German silver clamped solidly between upper and lower plates, s^5 , and separated by suitable insulation. Upon the spindle are mounted the wipers, s^6 , s^7 , s^8 , the latter being a connected pair adapted to rub against both faces of the single contacts in the banks, s^3 , and the former being separate wipers adapted to rub upon opposite faces of the pairs of contacts in the bank, s^2 . Connection is established with these wiper springs through a flexible cord or similar means, which I have not deemed it necessary to show.

The spindle, s^4 , is a long, straight piece of steel, journaled in the upper and lower members of the frame, s , so that it can both turn and slide therein. Its own weight normally keeps it down in the position shown in Fig. 10, with the wipers out of alignment with any of the contacts. The parts are not drawn to scale, but it is supposed that the first upward step of the spindle produced in the operation of the vertical magnet will bring the wipers opposite the respective first rows of contacts in the banks, and each successive step upward will shift the wipers opposite another row. After being stepped up until the wipers are opposite the desired rows, the spindle is then supposed to be turned one step at a time by the rotary magnet until the wipers rest upon the contacts of an idle trunk. For the purpose of effecting these vertical and rotary movements, the spindle carries two ratchets, s^9 , s^{10} , the former having a number of annular teeth, usually eleven or twelve, and the latter having a circular series of vertical straight teeth, which usually do not extend entirely around the ratchet surface, but only far enough to cover the arc through which the wipers must sweep when passing over all the contacts in a row. The vertical movement of the spindle is effected by the magnet, v , and the rotary movement by the magnet, r , both being mounted on the frame. The magnet, v , has an armature, v' , drawn down by a spring, v^2 , and carrying a pivoted pawl, v^3 , provided with a tail spring, v^4 , which tends to throw the tip of the pawl into engagement with the ratchet, s^9 , but is normally prevented from doing so by the stop pin, v^5 , set in the back plate, s^{11} , which is supposed to cover the entire back part of the frame, s . When the magnet, v , is energized it draws up its armature, v' , and the point of the pawl, v^3 , is immediately thrown forward to engage the upper tooth of the ratchet, s^9 , the continued upward motion of the armature then raising the spindle and its wipers one step.

The rotary magnet, r , has an armature, r' , appearing edgewise to the observer, in Fig. 10, and pivoted at its nearest edge in a ver-

tical line, so that the edge away from the observer swings to and from the magnet poles, moving the extended arm, r^2 , back and forth, and by means of the terminal pawl, r^3 , turning the ratchet, s^{10} . The pawl normally remains out of engagement with the ratchet, the armature being retracted by the spring, r^4 .

In order to retain the spindle in any position to which it may be raised and turned by the magnets, v , and r , I provide a pair of swinging pawls, t' , t^2 , whose ends engage the respective ratchets, s^{10} , and s^9 , and whose bell-crank body, t^3 , is pivoted between posts, t^4 , t^5 , at the edge farthest from the observer. Upon the front edge of the body is a projecting pin, t^6 , adapted to be engaged by the link, t^7 , on the upper end of the armature lever, t^8 , of the release magnet t . The link and the lever are normally drawn over by the spring, t^9 , into the position shown in Fig. 10. The pawls, t' , t^2 , are normally held in engagement with their respective ratchets by a suitable spring, not shown. When the magnet, t , is energized it draws over the lower end of the armature lever, t^8 , to the right, throws the link, t^7 , to the left until it passes over and engages the pin, t^6 ; and when the magnet is again deenergized the spring, t^9 , again draws the link to the right and swings the bell-crank body, t^3 , upon its pivots so as to raise the pawls, t' , t^2 , from their ratchets and permit the spindle to be rotated so as to disengage the wipers, s^6 , s^7 , s^8 , from the rows of contacts and then to drop into the normal position of disuse. At the end of its travel the link, t^7 , passes off the pin, t^6 , and the pawls are restored to engagement with the ratchets.

These are the operating members of the switch, in addition, the switch frame carries an escapement or controlling magnet for the side switch and for certain contacts which will be specified in the description of the circuits. The side switch is shown in front view in Fig. 10, at u . It consists of a plurality of switch-arms mounted one over the other with interposed insulation, the entire set being carried upon a lever, u' , pivoted at u^2 , and normally held in the position shown, against the tension of the spring, u^3 , by the engagement of the upper end, u^4 , with the first one of a number of teeth, u^5 , carried upon the armature lever u^6 , and constituting an escapement. Whenever the magnet, U , is energized the lever, u^6 , is thrown over to the left, the tip, u^4 , passing a half step to the right, when the armature is again retracted the tip passes a full step to the right, and so on, two steps placing the arms, u , successively in contact with the first, second and third sets of fixed contact points, u^7 , on an insulating block carried by the frame. When the switch spindle is all the way down in its normal

- position the lower edge of the ratchet wheel, s^{10} , engages the short upper arm of the bell-crank lever, u^8 , whose lower arm engages the lever, u' , to push the same back into initial position as shown in the figure.
- The magnet, U, at certain times has its armature mechanically held up, and for this purpose a projecting finger r^5 , is attached to the armature, r' , of the rotary magnet, r .
- Upon the upper part of this finger a button of insulating material is placed to engage and normally keep closed a pair of contacts, r^6 , in the circuit of the magnet, r . These contacts and the projecting finger, r^5 , are used only in the selector switch, in which the rotary movement is accomplished by constant and automatic vibrations of the armature, r' , until an idle trunk is found by the wipers.
- The magnet, U, controls a set of contact springs, u^5 , u^6 , the former normally closed, and the latter normally open. When the armature, u^6 , is attracted the conditions of these springs are reversed.
- In order to restore the spindle to its normal position in a rotary direction, a coiled spring is provided housed in a cap, s^{12} , at the top of the spindle, one end of the spring being attached to the same, and the other end to a lever arm, s^{13} , loosely journaled at one end on the spindle between the cap and the collar, s^{14} , and loosely sliding at the other end on a post, s^{15} . The collar, s^{14} , carries the stop arm, s^{16} , which abuts against a turned down leaf on the arm, s^{13} , when the parts are normal. The travel of the arm, s^{13} , up and down the fixed post, s^{15} , and the vertical extension of the ratchet, s^{10} , enables the spindle to be turned and restored through its full sweep in any vertical position.
- Having thus described the mechanical parts a knowledge of which is essential to the comprehension of my circuits, I turn to the description of the latter, beginning with Fig. 1. Therein I have shown three subscribers' stations, A , A' , A'' , each equipped with a telephone transmitter, a receiver, a switch-hook, a ringer, and condenser, all of usual or any suitable type for use with common battery circuits. When the hook is up, that is when it is relieved of the weight of the receiver, the circuit is through the transmitter and receiver; and when the hook is down, the line-circuit is completed for alternating current only, through the ringer and condenser. At each station I have shown a sender or signal transmitter for the use of the subscriber. At station A this is a key, and at each of the other stations it is a rotary wheel with pins, the designating letter in all three cases being K. Since the circuits are the same for all the lines, I will refer to the line from station A only. This consists of conductors 1 and 2, extending from the substation to the central office. At the substation the talking circuit is completed through the wires 3-4 when the hook is up, and the ringing circuit through the wires 5-6 when the hook is down. These figures are useful for the purpose of tracing the circuits only.
- Turning now to Fig. 2, the line-wires 1 and 2 appear at the left-hand side of the figure, terminating in contacts of the cut-off relays, M' , which are normally deenergized, so that in each case the line-wire 2 is grounded at 7 and the line-wire 1 extended through wire 8 to the line-relay M, and so to main battery B and ground. The armature, m , of each line-relay M is grounded at 9, and when attracted is adapted to close upon terminal contacts of wires leading to the tens and units relays of the primary selector sets. I preferably divide all the incoming lines in an exchange into groups of say one hundred each, and to each group I apportion a fixed number of trunks leading to connective apparatus. In a small or comparatively inactive exchange the percentage of these trunks may be as low as five, and in busy exchanges it may be raised to ten or even fifteen. I assume, however, that ten per cent. of connective apparatus will be sufficient to care for the present system, hence I provide ten trunks for each one hundred lines, and a complete set of tens and units relays in a primary selector group for each trunk. The circuits herein illustrated show six lines, which for convenience I will call Nos. 500, 501, 502, (Fig. 2) and 510, 511, 512, (Fig. 3). The subscribers' circuits of Fig. 1 will fit any of these, and in order to fully comprehend the connections of these lines and the arrangement of the tens and units relays, it is necessary to consider Figs. 2, 3 and 4 together. In Figs. 2 and 3 the subscribers' extension lines are shown coming in to their initial terminals on the tens relays, which are of the type shown in Figs. 8 and 9. Each of these relays carries the terminals of ten lines, and for each trunk there are ten of these relays, so that for 100 lines, provided with ten trunks, there will be 100 ten point relays, containing 1,000 line-terminals; from which it appears that each line can be multiplied ten times, which it should be in order to obtain access on occasion to every one of the ten trunks. The contacts on the ten point relays are arranged in duplicate pairs. That is, the incoming lines terminate each on one pair of springs, opposite which another pair of springs appears to which the line is connected when the relay is energized, and from which a local circuit passes to the front contact springs of a particular units relay or single point relay. For each group of ten tens relays there are ten units relays, or twenty relays in all for each trunk. A group of this kind constituting one primary selector

or trunk terminal for thirty lines, is shown in Fig. 7, apart from the other figures, so as to free the lines from their multiple connections. In order to make clear the connection of a line coming into the exchange, I will first refer to this figure and then trace the circuits through the others.

In Fig. 7, N, N', N², are three relays of the type shown in Figs. 8 and 9, having ten pairs of contacts each for the line-circuits. These relays correspond to the relays shown in Figs. 2 and 3, correspondingly lettered. At the top of the figure I have shown the terminal ends of lines 500 to 529, inclusive, connected to a pair of contacts, n³, n⁵, such as shown in the mechanical Figs. 8 and 9. For lines 500 to 509 these terminals are in the relay N. For lines 510 to 519 they are in the relay N'. For lines 520 to 529 they are in the relay N². Thus each relay contains line-terminals, n³, n⁵, for ten lines. When any one of the lines appropriated to a particular relay is calling, the electromagnet n', of that relay becomes energized. This will be explained in connection with the circuits of Figs. 1 and 2 farther on. For example, if any line from 500 to 509 originates a call, the magnet, n', of the relay N will become energized, and simultaneously connect all of the lines from 500 to 509 onto the extensions 10 to 19, inclusive. If, however, the calling line is in the group from 510 to 519, the magnet, n', of the relay, N', will become energized, connecting all that group onto the extensions 10 to 19, inclusive. Similarly, if the calling line be in the third group, from 520 to 529, the magnet, n', of the relay N², will be energized, connecting that entire group onto the extensions 10 to 19, inclusive. Thus extensions 10 to 19 are seen to be common to all of the tens relays, and in fact each extension pair is multiplied to corresponding contacts in all of the tens relays. No. 10 extension goes to the first pair of contacts, n⁴, n⁶, in each of the relays, N, N', N². Extension No. 11 is multiplied to the second pair of contacts, n⁴, n⁶, in each of the relays, and so on with all the extensions up to No. 19.

At the lower edge of Fig. 7, I have shown ten units relays, marked P to P⁹, inclusive. These are the same as the relays in Fig. 4, similarly marked. Each is a simple, standard relay, of the type in common use, and preferably of the same general type as that shown in Figs. 8 and 9, hereof, viz., that type in which the electromagnet is mounted horizontally on a frame or rack, carrying the contact springs upon it, and the whole is inclosed within a dust-proof shell. Each relay has an armature, p², adapted to be actuated by an electromagnet, p', to close together the contacts, p³, p⁴, and p⁵, p⁶. In the present instance, that is in the trunk group of each primary selector, all of the

contacts, p⁵, of the entire set of relays, P to P⁹, are connected together and all of the contacts, p⁶, are connected together, forming a set of double parallel branches marked 20 to 29, inclusive, which are really so many bridges across the trunk circuit, 30-31. This trunk-circuit, as indicated at the letter, x, in Fig. 7, may pass to any preferred form of connective apparatus; for the automatic system herein fully illustrated the trunk terminals, x, pass directly to the bridging relay circuits shown in Fig. 5; for a manual system, they terminate in a cord-circuit of the same general type as the circuits of Fig. 5, but without the solenoid relays, these being unnecessary except where automatic switches are to be controlled.

The outfit shown in Fig. 7 is sufficient for 30 lines, and by its use any one of the lines, 500 to 529, may connect itself to the trunk 30-31, by merely closing its line-circuit, and energizing the appropriate tens and units relays. The energizing circuits are not shown in Fig. 7, but will be described in connection with Figs. 2, 3 and 4. They comprise parallel branches closed by the line-relay of each line when calling, one branch going to the appropriate tens relay, and the other branch going to the appropriate units relay, which thus become energized simultaneously and act in conjunction to connect that particular line and no other to the trunk. For example, suppose line No. 512 is calling the subscriber having taken down his receiver from the hook, so as to close his line-circuit as shown in Fig. 1, and energize his line-relay, M, shown in Fig. 2. This line-relay closes two branches, one leading to the tens relay, N', in Fig. 7, and the other leading to the units relay, P², which is the third in the set of ten. The actuation of the tens relay, N', connects all of the lines 510 to 519 onto the extensions 10 to 19, inclusive; but it will be observed that these extensions are open everywhere else, hence no effect is produced by this action alone. The third units relay, P², however, connects the third extension 12 to the trunk 30-31, through the branch 22, and by following the circuits in Fig. 7 it will be found that this connects the line 512 onto the trunk direct, whereupon the trunk relays become energized, and further proceedings may be had of a kind suitable to the system employed. If the trunk 30-31 terminates in a cord-circuit, then the action is the same as if a plug had been inserted in the subscriber's line-jack, and by using suitable means the subscriber will find himself connected directly onto the operator's telephone. If, on the other hand the automatic circuits be employed, then the subscriber will be able to proceed at once to manipulate the automatic switches to which the trunk 30-31 leads. Only one line is thus con-

nected to the trunk at a time, assuming of course that only one tens relay and one units relay of the same set be energized simultaneously. It is true that the tens relay connects all of its lines onto the extensions; but all of these extensions are open except the particular one which is closed onto the trunk by the particular units relay energized. It is also true that the extension thus connected to the trunk is multiplied to the corresponding pair of contacts in every one of the tens relays, but this produces no effect, because all but one of the tens relays remain deenergized.

Before passing from Fig. 7 it is necessary to call attention to the fact that only three tens relays are there shown, accommodating thirty lines. This limitation is due to the necessary limitations of a Patent Office drawing, and it is to be understood that the same principles apply to any desired group up to 100 or more. It is most convenient in a scheme like this to make use of the decimal system, using ten relays per trunk, ten lines per relay, and ten trunk multiples per line. For 100 lines there would be ten of the tens relays, N, N', N^2 , etc., but still only ten of the units relays, and each of the extensions 10 to 19, inclusive, instead of being multiplied three times, would be multiplied ten times, into all the tens relays.

Turning now to Figs. 2, 3 and 4 we have here the same relays described in connection with Fig. 7, but somewhat differently arranged. Only two tens relays and three units relays of each set or of each trunk are shown. I have assumed the numbers 500, 501, 502 for the lines entering Fig. 2, and 510; 511; 512 for the lines entering Fig. 3. The first three lines being within the same tens digit of each other go onto the same tens relay in each set. For the sake of convenience I have given the designating numerals of the relays coefficients, and have marked the three trunks in Figs. 4 and 5 so as to be readily followed. Thus in Fig. 2 all three of the lines come into the relay N , which is adapted to put them onto the extensions, 10, 11, 12, etc., leading to the units relays, P, P', P^2 , etc., in Fig. 4. (I should here remark that the tens relays in Figs. 2 and 3 are not shown with their full complements of springs, for the sake of simplicity. Each of them is supposed to have ten pairs of contacts, in accordance with the showing of Figs. 7, 8, and 9.) Each of the lines 500, 501, 502 not only terminates in contacts of the relay, N , but is multiplied to similar contacts in the relays $1N, 2N$, etc. There would be one of these added for each trunk, that is appropriated to the group of lines. In the present case I only illustrate three trunks, so that each line need be multiplied only three times.

In Fig. 3, the lines 510; 511; 512 are con-

nected to the tens relays, $N', 1N'$ and $2N'$ in the same manner as the lines in Fig. 2, each line being multiplied three times so that each may have access to any one of the three trunks. It will be understood of course that the relays, N, N' , of Figs. 2 and 3, and P, P', P^2 of Fig. 4 constitute one set, appropriated to the trunk 30—31, and have precisely the same relation among themselves and the same connections, as the set shown in Fig. 7. Similarly the relays $1N, 1N', 1P, 1P', 1P^2$ all belong to one set, appropriated to the trunk line 130—131. Similarly again, the relays $2N, 2N', 2P, 2P'$ and $2P^2$ belong to one set, appropriated to the trunk line 230—231. The extensions from the tens relays to the units are marked 10, 11, 12 for the first set, 110, 111 and 112 for the second set, and 210, 211 and 212 for the third set. As these of course bear a logical relation throughout, and follow the same arrangement as that in Fig. 7, it is thought no difficulty will be experienced in comprehending the meaning of Figs. 2, 3 and 4. If Fig. 7 is understood, the description of the other figures may be put into one sentence. They show several groups like Fig. 7, with the line-wires multiplied to each group instead of terminating as in Fig. 7 in single pairs of contacts.

The actual connections controlled by the relays N and P being thus understood, it is most important to explain the means by which I control these relays. Referring to Fig. 2, the line-wires 1 and 2 terminate as I have stated, in the contacts of the cut-off relay M' , through which they are normally connected to the line-relay M and ground. When the subscriber at station A takes the telephone from the hook, he closes his line-circuit, the line-relay M is energized, and the two branch circuits 50 and 51 are immediately closed. The branch 50 passes in multiple to one winding of each of the three tens relays, $N, 1N$ and $2N$, these relays being double-wound for the purpose of making them self-locking when attracted. Any one of these relays might thus be energized by any one of the three lines shown, but it is my purpose that only one of them shall be so energized at once, and that no two lines shall be able to energize the same relay at the same time. Hence, on the other side of these relays I take away the circuit-wires 54, 55 and 56 to three separate controlling means presently to be designated. Each of these relays has its locking coil open on one side, but adapted to be grounded by the relay itself in pulling up; and on the other side of this second or locking winding it is connected through a wire 57, 58, or 59 to controlling means similar to those I have just mentioned, and which will also be specified later.

The second branch from the line-relay is 130

- marked 51 for line 502; 52 for line 501; and 53 for line 500. In other words, each of these lines has a different units wire, which is proper, as will be apparent at once if Fig. 7 has been understood. The three wires, 51, 52 and 53 pass along the bottom of the Figs. 2 and 3 and into Fig. 4, where they terminate in the first or operating windings of the three relays, P, P' and P², also by multiples 70 in the corresponding windings of the relays, 1P, 1P', 1P² and 2P, 2P' and 2P². The three relays, P, P', P², since they belong to the same set, have a common return, 60, which is connected to the common return, 54 75 from the tens relays, N, N', of the same group or trunk. This wire 54 passes into Fig. 5, and certain contacts on one of the relays, by which it is controlled. This will be fully explained a little farther on. Each of 80 the units relays in Fig. 4 has a locking winding separated from the actuating winding, and each locking winding terminates on one side in a contact normally open but adapted to be grounded when the relay is energized. 85 20 All the locking windings of the first set or group have a common return, 61, passing to the wire 57, which is the control wire of the locking windings on the tens relays, N, N'. This wire 57 passes into Fig. 5 and is there 90 carried to one of the relays, by which it is controlled. 95 25 The actuating windings of the units relays 1P, 1P', 1P², have a common return, 62, passing to the wire 55 which goes to a relay 100 30 contact belonging to trunk 130-131. The locking windings of these relays, 1P, 1P', 1P² have a common return, 63, which goes to the wire 58, passing into Fig. 5 and there controlled by one of the relays, in the same 105 manner as in the first set. Similarly, the actuating and locking windings, respectively, of the units relays, 2P, 2P' and 2P² have common return wires 64-65, connected respectively to the wires 56-59, which pass 110 40 into Fig. 5 and are there controlled by the relay of the trunk No. 230-231.

It is thought the scheme will now be plain. Suppose that one of the line-relays, as that of line No. 502, pulls up. It grounds the 115 local circuits 50 and 51 and energizes whichever one of the tens relays, N, 1N or 2N happens to be idle, together with the appropriate units relay. This would be one of the three relays, P², 1P² or 2P² in Fig. 4. The 120 tens relay and units relay thus selected having pulled up, their locking windings are grounded, and hence they are maintained energized through the locking common return as long as a subscriber keeps his receiver off the hook, being finally deprived of current when the subscriber hangs up, so that the relays are then restored.

I have thus shown, first, a single trunk group of primary selector relays, and second 125 three such groups, or at least portions of

three groups, belonging to three several trunks, and having the subscribers' lines connected to them in multiple. I will now point out how a calling line is permitted to select an idle trunk only, by working idle 70 relays only. For this purpose it is necessary that I should refer briefly to Fig. 5. This figure shows portions of three trunk-circuits, each of which commences at the letter x on the left of the figure, which is supposed to be the terminal point of attachment of the selective set shown in the preceding figures and in Fig. 7. Since the three trunks are identical, I will describe the upper one 75 only, with its apparatus. The trunk-wires are numbered 30-31, and the control wires which accompany the trunk are marked 54-57. The wire 54 is the common return from the actuating circuits of all the relays, both tens and units, belonging to the trunk 30-31, and the wire 57 is the common return wire from the locking windings of the same relays. It will be perceived that each subscriber's line is shown in Figs. 2 and 3 to be 80 equipped with a cut-off relay, whereby the line-relay may be disconnected, and the line put through onto its extensions, the line itself being in fact normally disconnected from the contacts on the tens relays. Since the tens and units relays which act to put any calling line onto a free trunk must be maintained energized after the line-relay has been cut off, locking windings are provided on all the relays; and the common return 57 from these locking windings is taken 85 through the trunk solenoid relays, so that at the expiration of a communication all 90 may be restored, the continued actuation of any set of relays being thus controlled 95 through their own trunk. On the other hand, since only an idle trunk must be accessible to calling lines, I carry the control 100 wire 54 from the actuating windings of the relays of one trunk to the point where it can 105 be controlled by the condition of the next preceding trunk in becoming busy. Generally stated, the method adopted in this 110 last-named arrangement is this: Assuming all the trunks to be idle, the first trunk has its relays connected to battery. As soon as the first trunk becomes busy its tens and units relays which have been actuated to 115 make it busy are locked through the wire 59 controlled by its own solenoids; but the common return 56 from the actuating windings 120 of all the other relays of the same set is disconnected from the battery, so that no other line can come in on the same trunk. Simultaneously with this action, battery is supplied to the actuating windings of the next 125 trunk in order, and consequently the next call that comes in will go on to that trunk and lock the relays, thereby actuated, at the same time disabling all the other relays of the same group, and in turn putting bat- 130

tery onto the third trunk. If now one of the intermediate trunks becomes idle, while those on both sides of it are busy, it will immediately become available for further calls, because the preceding trunk being busy supplies it with current, and the succeeding trunk being busy its relays are locked and not disturbed by the freedom of the intermediate trunk. If now the succeeding trunk becomes idle, while the intermediate trunk remains so, the succeeding trunk will not thereby become available, because as long as the intermediate trunk is idle, everything that follows it in order is cut off. I wish to say at this point that while the description must proceed in a lame and halting manner, as if the operation were slow, in reality the actuation of this system is so quick as to be correctly called instantaneous. None of the relays herein shown require more than a small fraction of a second for the operation, and hence the different changes and shifting of the lines and trunks take place without any perceptible interval of time whatever. This would be dangerous, in that it might lead to confusion were it not for the careful provision made whereby all the relays are positive in their action. There is no marginal working; I do not cross-connect any relays to work in opposition to each other, nor do I depend upon time intervals between relays of the same type. The only way that two lines can interfere by coming on the same trunk at the same time, is for them to close their line-circuits, and perform all of the resulting operations within an interval of less than say one-tenth of a second. The figure representing the probability of such a concatenation is so small as to be absolutely negligible.

Referring now to Fig. 5, I have therein shown what is really the connecting link between the primary selector portions of the circuit and the automatic connector portions of Fig. 6. All the apparatus in Figs. 2, 3 and 4 is merely for the purpose of answering calls and connecting the calling lines onto the circuits of Fig. 5, which I have called "trunks" for want of a better term. In other words, the relays of Figs. 2, 3 and 4 take the place of operators in plugging in with an answering plug, when a subscriber calls. In Fig. 5, the three trunks are shown as 30—31, 130—131, and 230—231. These come in at the left-hand side of the sheet, and terminate at condensers, C, C. On the other side of the condensers, and passing out at the right-hand side of the sheet are the extension trunk wires 70—71, 170—171 and 270—271. As all three of these trunks are the same, I will describe the upper one only. This comprises the two main or talking circuit wires 30 or 31, with their condensers, C, C, and

their extensions, 70—71, which pass into Fig. 6 and there connect with the automatic selector switch, S. Bridged across the wires 30—31, in the branches 72—73, and with the main battery B between them, are the trunk relays, D, D'. The relay, D', controls the battery supply in each case to the wire 74 and thence through the armature, d, of the relay, D, to the contacts of that relay. The relay D' becomes energized as soon as a line is connected to the trunk 30—31, a path for battery current being then immediately formed out through the line and back, and also to ground through the cut-off relay M'. This relay is therefore held up as long as the line is on the trunk, by current through the cut-off relay. The relay D on the other hand responds to the movements of the subscriber's hook and is employed for the purpose of repeating the impulses from the calling line into the switch circuits of Fig. 6. The manner of doing this will sufficiently appear from the statement of operation hereinafter. It suffices at this moment to say that when the armature, d, is back, the solenoid relay Q is drawn up, and when the armature, d, is up the solenoid relay Q' is drawn up. These solenoid relays are preferably made with their spools set vertically, the windings surrounding inner tubes within which the cores slide up and down after the fashion of plungers in dash-pots. The upper ends of the tubes are fitted with small check valves opening outwardly, so that each core may be drawn up quickly, but will retract or fall down very slowly. The solenoid, Q, performs several functions. To understand these perfectly it is necessary to have in mind the type of automatic selector and connector switches which I employ. These may be of any well-known or suitable type, such as those which I have myself designed, but they are herein shown for convenience as of the Strowger or automatic electric type. In order to operate this type of switch, the actuating impulses are sent over one side of the line, and the controlling or shifting impulses are sent singly over the other side. In finally releasing and restoring the switches, an impulse is sent over both sides of the line simultaneously. In my circuits, the actuating impulses are transmitted over the trunk-wire 70, in groups corresponding to the digits of the number wanted. The controlling impulses are sent over the wire 71, singly, and in between groups of actuating impulses. For example, suppose the number wanted to be 468, four impulses go over the wire 70, then a single impulse over the wire 71, then six impulses over the wire 70, then another single impulse over the wire 71, and finally eight impulses over wire 70, followed by another single impulse over wire 71. The purpose of my solenoids, Q,

Q' , is to produce these impulses in the two wires 70 and 71 in their proper order and arrangement, in response to makes and breaks only in the metallic circuit 30—31; 5 for it will be observed that at the subscribers' station in Fig. 1 I show no grounds, all of my present designs dispensing with grounds outside the central office. The solenoid, Q' , pulls up at the first energization 10 of the relays, D, D', and stays up until the subscribers finally clear out. In coming up it opens the contacts 92 and 93 and closes the contacts 90 and 91, these latter being together with the contacts 85—86 of solenoid Q, the controlling contacts of the relay locking circuit 57. At the first break produced by the sender or key, K, at the subscriber's station, after the line has become connected, the armature, d , falls back for 15 an instant, and the solenoid, Q, pulls up. The impulses into wire 70 are repeated direct by the armature, d , by way of the wire 80, contacts 87—88 and wire 89. The contacts 87—88 are closed together when the 20 solenoid pulls up. The contacts 84 are momentarily closed as the solenoid pulls up, without effect, because they derive current from the wire 81 attached to the front contact of the relay D, which is open when the 25 solenoid pulls up and closed when it falls down. The latter movement takes place between the groups of impulses, and a single pulse of current is then sent by way of wire 83 to the wire 71. The solenoid, Q' , is thus 30 seen to be really the clearing out solenoid, while the solenoid, Q, is really the controlling or actuating solenoid.

The wire, 54, it will be recalled, is the common return for the actuating circuits of all 40 the primary selector relays appertaining to the trunk 30—31. This actuating circuit derives its current from a normally closed back contact of the armature, d' , of the relay, D'; and this armature, d' , derives its 45 current in turn through the wire 98 from the wire 74 controlled by the relay, 1D' of the next trunk 130—131. This battery supply circuit may be traced as follows: battery B, wire 75, armature d^2 of the relay 50 2D', wire 74, 77, 99, armature d' of the relay 1D', wire 98, armature d' of the relay D', to wire 54. The common return 55 from the actuating coils of the relays of this trunk 130—131 takes current from a back contact 55 of the armature, d' , of the relay, 1D', which in turn derives its current through the wire 99 from the wire 74 of the preceding trunk 230—231. The common return 56 from the 60 actuating windings of the relays appertaining to this last trunk, derives its current from a back contact on the armature, d^2 , of the relay 2D', this deriving its current from the main battery. The effect of this arrangement is to make the trunk 230—231 65 normally active, since its relays, 2N, 2N';

2P, 2P', 2P² are normally on the main battery; but all the other trunks are normally inactive. As soon as a calling line becomes connected with the trunk 230—231, the relays 2D, 2D', pull up, the common return wire 56 is disconnected from battery, the pair of relays that have already pulled up remaining energized by their locking coils through the wire 59, but all the other relays of that set, tens and units alike, being 70 disabled by the cutting off of the common return. At the same time, battery is put on the wire 77 leading to the next trunk 130—131, and through the armature, d' , of the relay, 1D', thereof, to the wire 55, which 75 is the common return of the relays, 1N, 1N'; 1P, 1P', 1P², etc.; of that trunk. The next call will therefore find the trunk 130—131 active, and as soon as that trunk has become 80 connected, it will in turn cut off its own actuating coils, except those we have already operated, and will shift the battery to the next trunk 30—31 through the wire 98. When that trunk operates, it will cut off its 85 own actuating common return 54 in the same 90 way, and throw battery onto the wire 77 to render the next succeeding trunk active, and so on.

Referring now to Fig. 6, which completes the chain of circuits, two switches are there 95 in shown, as types of an organization sufficient to serve 1,000 lines. These switches are, in ordinary technical parlance, a "second" selector, S, and a connector S'. I have described the mechanical construction of 100 these switches as shown in Figs. 10 and 11, so it will merely be necessary to refer briefly to the circuit connections before passing to the operation of my system as a whole. The wires 70, 71 terminate in switch-arms, 2^u, 3^u, 105 of the side switch of the second selector, S. It should be explained that the present equipment being for 1,000 lines or less, it is only necessary to have these two sets of switches, the second selector, S, serving to 110 pick out the desired hundreds group wanted; and the connector switch, S', of that group then serving to pick out the desired tens and units. The switch-arms, 2^u and 3^u, normally rest upon terminals of wires 100 and 115 101, connecting the vertical and rotary relays, V and R to the wires 70 and 71, and maintaining this connection until the third step of the switch. The wires 118 and 119 leading to the wipers 8⁶, 8⁷, are normally 120 open, and the test relay T has its circuit 142 also normally open at the switch-arm, 4^u. The connector switch has the same parts as the selector switch, with some additional parts. The vertical magnet, v, is the same, 125 but the rotary magnet, r, does not have the vibrator contacts, r⁶, responding only to single impulses. The vertical and rotary relays, V', R', control the magnets, together with the private or controlling relay, U'. 130

The side switch-arm, 1^u, makes connection in its last step with a ringing relay, *g*, controlling the connection of the generator, *G*. In order to supply talking battery to the called subscriber, a pair of bridging magnets, *E*, *E'*, is employed, with the main battery *B* between them.

In Fig. 12 the whole system is shown reduced to an elemental diagram in which the various elements are indicated conventionally and in their proper connective relation to each other, a single line indicating a pair of conductors. This figure clearly shows how the individual lines may be connected with any group of primary selectors by "jumpers" in the intermediate frame.

The operation of the complete system thus described is as follows: We will assume all the trunks in Fig. 5 to be idle, all the relays in Figs. 2, 3 and 4 to be deenergized, and the switches in Fig. 6 to be in their normal or zero position, as therein shown. Under these circumstances assume that subscriber A calls, by removing his receiver from the hook, desiring to talk with subscriber No. 468. As soon as the receiver has risen the following circuit is closed: *B*, *M*, 8, 1, 3, 4, 2, 7, and ground to *B*. Relay *M* at once pulls up, grounding the wires 50 and 51, and closing the following two circuits: first, *B*, (Fig. 5) 75, (of the lowest trunk) *d'*, of relay 2D', 56, through Figs. 4 and 3 into Fig. 2 to the actuating winding of relay 2N, by wire 50 to relay *M*, and ground; second, *B*, 75, (same trunk) 56, into Fig. 4, 64, to the actuating winding of relay 2P², 51 to relay *M*, and ground. The two relays, 2N and 2P² therefore pull up. The relays of the other trunks are all inactive, although it will be observed that the wires 50—51 from the relay *M* have multiple connections to them, for the reason that the battery is cut off from each of the wires 99 and 98, through which the wires 54 and 55 to all their actuating windings are supplied. The relay 2N connects the lines 500, 501, 502, etc., onto the extensions 210, 211, 212, etc., but all of these extensions remain open except one, 212, which is closed by the relay 2P² onto the trunk-wires 230—231. The pulling up of these two relays therefore has closed the following path through the trunk and line: *B*, 75, 2D', 231, one contact of 2P², 212, to one contact of 2N, 502, to the front contacts of the cut-off relay *M'*. The main battery being grounded, the cut-off relay instantly takes current, and pulls up, whereupon the circuit is continued as follows: 2, 4, (at substation A), 3, 1, 502, through the other contact of relay 2N to extension 212, back to the other contact of relay 2P², to the wire 230, relay 2D, and ground. The bridging trunk relays 2D and 2D' thereupon pull up instantly, with the following effects: The relay 2D' cuts off the actuating

wire 56 from the battery wire 75, disabling all the relays of its set except the two that have already pulled up, both of which have grounded their locking windings, which thereafter derive current through the wire 79 59, and the closed contacts of the solenoid relays, *Q*, *Q'*. At the same instant that the wire 56 is cut off to disable this trunk for further calls, the relay 2D' connects the battery wire 75 with the wire 77 leading to the armature *d'* of the next trunk 130—131. The actuating wire 55 of that trunk thereby becomes connected to battery, and the next call from any of the six lines I have shown, or others in their set, will result in a connection with the second trunk.

Returning to the first trunk, we find that the pulling up of the bridging relays puts battery on the solenoid *Q'* by the following path: *B*, 75, armature *d'*, 74, armature, *d*, 81, *Q'*, 95, to ground. This solenoid pulls up at once, breaking apart the springs 92 and 93 and closing together the springs 90 and 91. These latter springs are in the circuit of the locking wire 59, putting battery 90 thereon by way of the wire 750, which is connected to battery the same as the wire 75. The locking circuit is also closed in parallel through the springs 85 and 86 of the solenoid *Q*, which does not pull up as yet.

The foregoing action, as I have stated before, takes some little time to describe, but it is really instantaneous, so the subscriber after taking down his receiver proceeds to tap the key, *K*, four times, and then waits 100 for a few seconds. Each of the four taps produces a series of short breaks in the circuit 1—2 and interrupts the flow of current through the relay 2D in Fig. 5. The armature, *d*, falls back four times, each time pulling up again very quickly as the circuit is again closed. At the first falling back the circuit of the solenoid, *Q*, is closed as follows: *B*, 75, *d'*, 74, *d*, 80, solenoid *Q*, 96, to ground. This solenoid instantly pulls up, and in so doing it momentarily closes together the springs 84, opens the springs 85—86, and keeps the springs 87—88 closed. Meanwhile, it should be noted the solenoid, *Q'*, remains up, since the breaks in its circuit 81 are of such brief duration that its core does not have time between the makes to drop down as far as the springs. The closure of the springs 84 produces no effect, since they derive their current through wires 110 82 and 81, which are open when the solenoid, *Q*, is energized. The springs 85—86 are in the locking circuit, as I have said, but their opening does no harm, since a shunt is closed around them through the springs 115 90—91 of the other solenoid. The springs 87—88 close the circuit of wire 89 to the wire 270. Each time the armature, *d*, falls back in response to the subscriber's break, an impulse goes through the wire 89 to the 120 125 130 effects: The relay 2D' cuts off the actuating

wire 270 and to the selector switch S, by the following path: B, 75, 74, d, 80, 87, 88, 89, 270, 70, (in Fig. 6), 2^u, 100, V and ground. Relay V pulls up and closes the circuit of the vertical magnet, v, once for each impulse, as follows: B, 108, 109, v, 115, u⁸, 104, 103, 102, and ground. The spindle s⁴ is thereupon stepped up four steps, bringing its wipers, s⁶, s⁷, s⁸, opposite the respective fourth rows, which contain terminals of trunks passing to connector switches containing the contacts of lines from 400 to 499. When the subscriber pauses after making the four taps, the relay 2D, in Fig. 5, remains energized, for a long enough space of time to permit the solenoid, Q, to drop its core all the way down. In so doing the core closes the springs 84 momentarily, and a single impulse is sent over the wire 271 by the following path: B, 75, d², 74, d, 81, (the relay 2D remaining energized during the pause) 82, 84, 83, 271, 71, (Fig. 6), 3^u, 101, R, and ground. Relay R thereupon pulls up, and closes the circuit of relay U, which pulls up, opening the circuit 115 of the vertical magnet, v, at the springs u⁸, and shifting the side switch one step. This closes the circuit of the rotary magnet, r, as follows: B, 108, 109, r, (by way of r⁶) 116, 1^u, 117 and ground. The magnet, r, thereupon commences to turn the spindle, and the wipers, s⁸, pass over the terminals, s³, of the trunks to the connector switches in the 400 group, testing to find an idle one. The armature of the relay U is kicked up by the armature of the rotary magnet, r, as heretofore explained, and in between the kicks is held up by ground on the successive contacts, s³, if they are busy. As soon as one is found that is not busy, the relay, U, lets go between the kicks, the side switch is permitted to make its third step, and the circuit of the relay U, which has heretofore been through the wires 143, 142 to the wiper s⁸, is broken by the arm, 4^u, passing to the third contact, thereby grounding the wiper s⁸ and whatever trunk contact, s³, it rests upon, to make the same test "busy" for other switches. The subscriber now makes six taps on his key, producing the same effects in the trunk circuits of Fig. 5 as before, but this time the six resulting impulses come over the wire 70 in Fig. 6, and go through the switch-arm 2^u and through the wire 118 and the wiper s⁶ to the connector contact, s², which has been selected as idle, through the trunk-wire 120 to the vertical relay, V', of the connector switch, S', and so to ground. The relay, V', pulling up works the rotary magnet, v, of the connector switch over the following circuit: B, 128, 134, v, 132, 1^u, 135, u⁸, 137, 138 and ground. The spindle, s⁴, of the connector switch is thereby stepped up to the sixth row of contacts. The subscriber then pauses and

a single impulse comes over the wire 71, 65 switch-arm 3^u, wires 119, 121 to the rotary relay R' and ground. This relay pulls up, and closes the circuit of the private magnet U' as follows: B, 145, U', 147, 138 and ground. The magnet U' thereupon pulls up, breaking the vertical magnet circuit at u⁸, and shifts the side switch one step. (It should be noted here that all the arms, u, move together.) The rotary magnet, r, is now connected to the wire 135, instead of 75 the vertical magnet, v, and when the subscriber taps his key eight times to send the last digit, the eight impulses come over the wires 70 and 120 to the vertical relay V' as before, but that relay now works the rotary magnet, r, over the following circuit: B, 128, 134, r, 129, 1^u, 135, u⁸, 137, 138 and ground. This turns the spindle to contact No. 8 in the sixth row of the 400 connector switch, thereby setting the wipers s⁶, s⁷ on 85 the desired line. As the subscriber relinquishes his key for the last time, the solenoid, Q, in Fig. 5 sends the last rotary impulse over the wires 71 and 121 to the relay R', which again energizes the private magnet U', and that magnet pulls up. Now, it will be recalled that the escapement controlled by this magnet has two sets of teeth and requires a double movement for each single progression of the side switch-arms; 95 hence as this magnet pulls up, and before the side switch has moved, a test circuit is closed through the test relay, T', from the tip side wiper, s⁶, as follows: s⁶, 146, 4^u, 144, u⁸, T', 140, battery and ground. If the line wanted 100 is busy, it is grounded on the tip side, either through a bridging coil, E, (Fig. 6) or through a bridging relay, 2D (Fig. 5), depending upon whether it has been called or has made the call itself. In either case, if 105 the tip side is grounded, the test circuit I have just traced will be completed, the test relay, T', will pull up, the circuit of the release magnet, t, will be closed, and the connector switch will go back to zero. When 110 the calling subscriber hangs up he will restore the rest of the apparatus, in the same manner as if he had finished the conversation, which will be described further on. If the line wanted is not busy, this test circuit 115 will not be closed, and the side switch will move the final step, so that the talking circuit is completed straight through by way of the wires 70, 118, 120, 123, 124 on one side, and 71, 119, 121, 175, 125, on the other. Having thus secured his connection the subscriber may ring by simply tapping his key or turning his hand-wheel an indeterminate number of times. He cannot disturb the switching magnets by so doing, for they are 120 all cut off, and the only thing he must guard against is leaving his circuit open for more than a very brief interval at once. He can

send as many short breaks as he pleases, and these will work the vertical relay, V' , and through that the ringing relay, g . Each time the latter is energized it breaks the 5 connector circuit and puts the generator, G , onto the wires 123, 175 and thence to the called line.

After the called subscriber has answered, and the conversation has been finished, both 10 subscribers hang up. I can arrange these circuits so as to give the two subscribers joint control, but I prefer to give this control to the calling subscriber, which I consider better practice. As soon as this calling 15 subscriber has hung up, the circuit through the relay 2D in Fig. 5 is broken, and that relay lets go its armature. The first effect of this is to pull up the solenoid, Q , and since the armature remains back, to deenergize 20 and let go the core of the solenoid, Q' , the energization of solenoid Q breaks the locking contacts 85 and 86 of the locking wire 59 and closes the contacts 87 and 88, so as to put battery on the wire 270 by the following 25 path: B, 75, d' , 74, d , 80, 87, 88, 89, 270. The retraction of the core of the solenoid, Q' , closes the springs 92 and 93 and opens the springs 90-91, the latter being its pair 30 of locking springs belonging to the locking circuit 59. In this condition, therefore, it will be observed that the locking wire 59 is open at both solenoids, so that the relays 2N and 2P² become deenergized, and disconnect the line 502 from the trunk 230-231. The 35 closing of the springs 92-93 of the solenoid, Q' , puts current on the rotary wire 271 by the following path: B, 75, d' , 74, d , 80, 92, 93, 83, 271. Turning now to Fig. 6, and remembering that we have current coming 40 over both wires 270-271 (or 70-71, which is the same thing since these numbers indicate duplicate trunks), we find that both relays, V' , R' , take current at once, whereby the following circuit is closed, for the release magnet: B, 145, 140, T', 139, 136, s^3 , s^8 , 142, T, 4^a, 141, and ground. Both relays, T and T' become energized, closing the circuits of their respective release magnets, t , t' . Both switches S, S', are thereupon released 50 and restored to their normal position of inactivity, as shown in Fig. 10.

The breaking of the locking circuit 59, and the consequent deenergization of the relays, 2N and 2P², disconnect the line from 55 the trunk, in the same manner, as the pulling out of a plug by an operator would do. The cut-off relay M' of the line thereupon loses current, lets go its armature, and again puts the line onto its signal relay M . All the 60 parts are then in position for another call.

It will be observed that the deenergization of the trunk relay 2D' in Fig. 5, puts battery back on the actuating circuit wire 56, there- 65 by again rendering active all of the relays

of its set in Figs. 2, 3 and 4, and at the same time battery is taken off of the wire 77 leading to the next trunk, hence if there is not a call already on the second trunk, 130-131, it will be rendered inactive, and any succeeding call will be taken up by the first 70 trunk, 230-231. If some line has called and has become connected with the trunk, 130-131, however, this connection will not be affected by the changes in the trunk 230-231; because the relays of each trunk after 75 being once actuated are not dependent on their actuating coils, but only upon their locking coils, which of course are energized through their own circuit-wires 57, 58 or 59 controlled entirely by conditions in their 80 own circuits.

For purposes of locking my relays I have shown double windings, but this may be varied by substituting double contacts, and single windings. I have found it so far to be 85 best to use double windings, because these windings being all on a common return, it is necessary if a single winding is to be substituted for each relay to cut itself off of the actuating circuit before locking itself on 90 the locking circuit. However, this is a matter of detail, and can be variously arranged by any one skilled in the art.

Referring to the diagram, Fig. 5, I desire 95 to call attention to the fact that while the battery wire 77 passing to the second trunk is taken off of the wire 74 of the first trunk (commencing at the bottom of the figure), the succeeding battery wires 98 and 77 are taken off the front contacts of the armatures, 100 d' , so that if the first two trunks are active and the third trunk is idle, battery will be supplied to the actuating wire 54 through contacts of the relays 2D' and 1D' in series. This arrangement seems to be necessary in 105 order to prevent confusion where intermediate trunks become idle. I do not limit myself to the specific arrangement shown, however, nor to any of the specific details herein described, being fully aware myself of many 110 changes that may be made without departing from the spirit of the invention, and also aware that many other changes must suggest themselves to workers in the art.

It will be understood that suitable 115 resistances are to be included in the ordinary and well-known manner between the battery and various pieces of apparatus in order to prevent too much current passing. Where pieces of apparatus are grouped in the manner shown herein, paths of low resistance 120 may be formed which would permit an injurious amount of current to pass. I have shown such a limiting resistance between the wire 75 and the armature d^2 of the relay 125 2D', and similar resistances are supposed to be inserted wherever required. In order to still further protect the system of wiring

from accidental short circuits and the like, which occur in all complicated networks, I may employ the usual expedient of inserting fuses or other protective devices in the various battery leads. All such expedients are common and well known, however, and need no specific description or illustration.

Having thus described my invention, what I claim and desire to secure by Letters Patent is:—

1. In a telephone exchange system, a plurality of subscribers' lines each having a fixed and determinate resistance, a plurality of connective circuits less in number than the number of lines, a group of relays associated with and individual to each connective circuit, adapted to selectively connect a calling line with their connective circuit, means also associated with each connective circuit for selecting and connecting with a wanted line, together with means for energizing the relays responsive to the closure of a calling line circuit, substantially as described.
2. In a telephone exchange system, a plurality of subscribers' lines, a connective circuit for interconnecting the lines, and a bank of coacting relays associated with and individual to the connective circuit and containing terminals of the lines, together with means responsive to the closure of a calling line circuit to connect the same automatically through selected relays in the bank with the connective circuit, substantially as described.
3. In a telephone exchange system, a plurality of subscribers' lines, a plurality of switching or connective circuits, and selecting relays associated with and individual to the respective switching or connective circuits but adapted to be directly controlled by closure of the subscribers' lines when calling to connect the same with the connective circuits, substantially as described.
4. In a telephone exchange system, a plurality of subscribers' lines, a plurality of switching or connective circuits, and selecting relays associated with and individual to the respective switching or connective circuits but adapted to be directly controlled through the closure of the subscribers' lines when calling to connect the same with the connective circuits successively as they become idle, substantially as described.
5. In a telephone exchange system, a plurality of subscribers' lines, a plurality of switching or connective circuits, and selecting relays associated with and individual to the respective switching or connective circuits but adapted to be directly controlled through the closure of the subscribers' lines when calling to connect the same with the

connective circuits, successively, together with means associated with each connective circuit for rendering active the selecting relays of the next connective circuit, substantially as described.

6. In a telephone exchange system, a plurality of subscribers' lines, a plurality of switching or connective circuits, and selecting relays associated with and individual to the respective switching or connective circuits but adapted to be directly controlled through the closure of subscribers' lines when calling to connect the same with the connective circuits, together with means associated with each connective circuit to disable its own selecting relays when it becomes connected with a calling line, substantially as described.

7. In a telephone exchange system, a plurality of subscribers' lines, a plurality of switching or connective circuits, and selecting relays associated with and individual to the respective switching or connective circuits but adapted to be directly controlled through the closure of subscribers' lines when calling, to connect the same with the connective circuits, together with means associated with each connective circuit to disable its own selecting relays when it becomes connected with a calling line, and at the same time to render active the relay selector of the next connective circuit in order, substantially as described.

8. In a telephone exchange system, a plurality of lines, a plurality of trunks or connective circuits, relays adapted to directly connect the lines with the trunks, automatic switches adapted to connect the trunks with wanted lines and circuits controlled by the closure of subscribers' lines and independent of the switch circuits for operating said relays, substantially as described.

9. In a telephone exchange system, a plurality of lines, a plurality of trunks or connective circuits, relays for directly connecting the lines with the trunks, actuating circuits for said relays controlled at the subscribers' substations through the closure of the line circuits, automatic switches for connecting the trunks with wanted subscribers and means associated with the trunk circuits and independent of the automatic switches for rendering said trunks when connected inaccessible to calling lines and for placing the trunk circuits in condition to be reached in succession by the calling lines.

10. In a telephone exchange system a plurality of subscribers' lines divided into groups, a plurality of relays for each group, each containing terminals of all the lines having the same tens digit, a second series of relays each having contacts connected with one definite contact in every one of the

tens relays, a trunk or connective circuit connected in parallel to all of the second set or units relays, and means to energize a definite tens and a definite units relay in order to connect the corresponding line with the connective circuit, substantially as described.

11. In a telephone exchange system a plurality of subscribers' lines divided into groups, a plurality of relays for each group each containing terminals of all the lines having the same tens digit, a second series of relays each having contacts connected with one definite contact in every one of the tens relays, a trunk or connective circuit connected in parallel to all of the second set or units relays, and means to energize a definite tens and a definite units relay in order to connect the corresponding line with the connective circuit, said means being controlled initially over a calling line, substantially as described.

12. In a telephone exchange system, a plurality of subscribers' lines divided into groups, a plurality of relays for each group each containing terminals of all the lines having the same tens digit, a second set of relays each having contacts connected with one definite contact in every one of the tens relays, a trunk or connective circuit connected in parallel to all of the second set or units relays, and means to energize a definite tens and a definite units relay in order to connect the corresponding line with the connective circuit, said means adapted to be controlled by the line relays of subscribers' lines when calling, substantially as described.

13. In a telephone exchange system a plurality of subscribers' lines divided into groups, a plurality of relays for each group each containing terminals of all the lines having the same tens digit, a second series of relays each having contacts connected with one definite contact in every one of the tens relays, a trunk or connective circuit connected in parallel to all of the second set or units relays, and means to energize a definite tens and a definite units relay in order to connect the corresponding line with the connective circuit, said means responding initially to current in any one of the lines of the group, and thereafter controlled through the connective circuit, substantially as described.

14. In a telephone exchange system, a plurality of subscribers' lines, a plurality of selective circuits less in number than the number of subscribers' lines, a switching device constituting one terminal of each selective circuit, a group of coacting relays having terminals of the subscribers' lines and forming another terminal for each selective circuit, together with means responsive to closure of the subscribers' lines

to energize said relays, substantially as described.

15. In a telephone exchange system, a plurality of subscribers' lines, a plurality of automatic switches for receiving calls and initiating connections, said switches being less in number than the number of subscribers' lines, and a plurality of groups of coacting relays individual to the several switches directly responsive to calls over the subscribers' lines to connect the same to the respective automatic switches, substantially as described.

16. In a telephone exchange system, a plurality of subscribers' lines, a plurality of connective circuits, a switching device at one end of each connective circuit and a group of coacting relays at the other end containing multiple terminals of the subscribers' lines, means for supplying current to the connective circuits and lines, means for energizing said relays so as to connect any given line with a connective circuit, and means for controlling said connection through the connective circuit and the subscriber's line, substantially as described.

17. In a telephone exchange system, a plurality of subscribers' lines, a trunk or connective circuit therefor, a group of coacting relays containing multiple terminals of the lines and responsive to the closure of any one of their line circuits when calling, to connect the same to the connective circuit, and means for rendering said relays irresponsible after such connection is effected, whereby only one line may become connected at the same time, substantially as described.

18. In a telephone exchange system, a plurality of subscribers' lines, a connective circuit, a group of coacting relays containing line multiples and responsive to the closure of any of their lines in calling to select and connect it to the connective circuit, means then becoming operative to remove the relays from line control, and means controlled by the connected subscriber through the connective circuit for maintaining his connection therewith, substantially as described.

19. In a telephone exchange system, a plurality of line circuits, a connective circuit, a group of coacting relays containing line multiples and responsive to the closure of any of their lines when calling to connect the same to the connective circuit, means for cutting off said relays from line control when so connected, and a relay associated with said connective circuit and controlled by the connected subscriber therethrough for maintaining his connection, substantially as described.

20. In a telephone exchange system, a plurality of line circuits, a connective circuit, a group of coacting relays associated

- therewith responsive to closure of the lines for connecting the same to the connective circuit, means whereby said relays upon being energized may lock themselves upon a control circuit, means for removing the relays when thus locked from line control, and means whereby a subscriber when connected may control said locking control circuit to the relays upon which his connection depends, substantially as described.
21. In a telephone exchange system, a plurality of line circuits, a number of connective circuits less than the number of lines, switching devices controlled by a calling subscriber to connect his line, means associated with the connective circuit and independent of the switching devices for rendering a busy connective circuit inaccessible to another calling line and for rendering an idle connective circuit accessible, and means also controlled by the subscriber to release said switching devices, substantially as described.
22. In a telephone exchange system, a plurality of subscribers' lines, a number of connective circuits less than the number of lines, banks of selecting relays respectively associated with and individual to the connective circuits and containing line multiple terminals, means to control the same responsive to the closure of calling line, and means to restore the same to idle or inactive condition at the end of each connection, substantially as described.
23. In a telephone exchange system, a plurality of metallic line circuits, a connective circuit, relays responsive to the closure of a line for connecting the same to the connective circuit, means whereby said relays upon being energized may lock themselves upon a control circuit, means for removing the relays when thus locked from line control, means whereby a subscriber when connected may control said locking control circuit to the relays upon which his connection depends, automatic switches for selecting and connecting a wanted subscriber, and means independent of said switches for rendering a busy trunk inaccessible to a calling line.
24. In a telephone exchange system, a plurality of line circuits, a connective circuit, relays responsive to the closure of the lines for directly connecting the same to the connective circuit, automatic switches adapted to be controlled over said connective circuit solely, means associated with said connective circuits and independent of said automatic switches for rendering said circuit when busy inaccessible to any other calling line, and for rendering the next idle connective circuit accessible to the first subsequent calling line.
25. In a telephone exchange system, a

plurality of subscribers' lines each having a fixed and determinate resistance, a plurality of connective circuits less in number than the number of lines, each connective circuit provided at one end with a group of relays in decimal relation adapted to selectively connect a calling line with their connective circuit, and at the other end with means for selecting and connecting with a wanted line, together with means for energizing the relays responsive to the closure of a calling line circuit, substantially as described.

26. In a telephone exchange system, a plurality of subscribers' lines, a connective circuit for interconnecting the lines, and a 80 decimally arranged relay bank associated with the connective circuit and containing terminals of the lines, together with means responsive to the closure of a calling line circuit to connect the same automatically 85 through the relay bank with the connective circuit, substantially as described.

27. In a telephone exchange system, a plurality of subscribers' lines, a plurality of switching or connective circuits, and relay selectors in decimal relation associated with the respective switching or connective circuits but adapted to be directly controlled by closure of the subscribers' lines when calling to connect the same with the connective circuits, substantially as described.

28. In a telephone exchange system, a plurality of subscribers' lines, a plurality of switching or connective circuits, and relay selectors in decimal relation associated 100 with the respective switching or connective circuits but adapted to be directly controlled through the closure of the subscribers' lines when calling to connect the same with the connective circuits successively as they become idle, substantially as described.

29. In a telephone exchange system, a plurality of subscribers' lines, a plurality of switching or connective circuits, and relay selectors in decimal relation associated 110 with the respective switching or connective circuits but adapted to be directly controlled through the closure of the subscribers' lines when calling to connect the same with the connective circuits, successively, together 115 with means associated with each connective circuit for rendering active the relay selector of the next connective circuit, substantially as described.

30. In a telephone exchange system, a 120 plurality of subscribers' lines, a plurality of switching or connective circuits, and relay selectors in decimal relation associated with the respective switching or connective circuits but adapted to be directly controlled 125 through the closure of subscribers' lines when calling to connect the same with the connective circuits, together with means as-

sociated with each connective circuit to disable its own relay selectors when it becomes connected with a calling line, substantially as described.

- 5 31. In a telephone exchange system, a plurality of subscribers' lines, a plurality of switching or connective circuits, and relay selectors in decimal relation associated with the respective switching or connective circuits but adapted to be directly controlled through the closure of subscribers' lines when calling, to connect the same with the connective circuits, together with means associated with each connective circuit to disable its own relay selectors when it becomes connected with a calling line, and at the same time to render active the relay selector of the next connective circuit in order, substantially as described.
- 10 32. In a telephone exchange system, a plurality of lines, a plurality of connective links, and relays less in number than the product of the number of lines by the number of links, adapted to be actuated so as to select and connect any line to any link.
- 15 33. In a telephone exchange system, a plurality of lines, a plurality of connective links, and relays less in number than the product of the number of lines by the number of links, adapted to be actuated so as to select and connect any line to any link, and as many lines simultaneously as there are links.
- 20 34. In a telephone system, a group of lines; a group of trunks; line relays pertaining to said lines; trunk relays less in number than the number of lines pertaining to said trunks; and service conductors associated primarily with said trunks and passing through windings of trunk relays to contacts of line relays; whereby the energization of trunk relays will result upon the energization of line relays, substantially as described.
- 25 35. In a telephone system; line conductors for speech current transmission; line relays associated with said line conductors; trunk conductors for speech transmission; trunk relays associated with said trunk conductors; circuits whereby, by the energization of a relay associated with a specific line, relays associated with a trunk are energized and connect the speech current conductors of that trunk with the speech current conductors of that specific line; and other circuits and apparatus whereby said action-initiating line relay is deenergized, substantially as described.
- 30 36. In a telephone system, a group of lines; substation telephone equipments on said lines; a group of trunks; line relays pertaining to said lines; trunk relays pertaining to said trunks; service conductors associated primarily with said trunks and

passing through windings of trunk relays 65 to contacts of line relays, whereby the energization of trunk relays will result upon the energization of a line relay; locking windings on said trunk relays whereby the energization is continued in trunk relays energized primarily through line relay contacts and subsequent to the deenergization of the line relay; and windings maintaining said locking dependently upon the continuance of current from the trunk to the connected 70 line and through the substation telephone equipment upon that line, substantially as described.

37. In a telephone system; a group of lines; substation telephone equipments on said lines; a group of trunks; line relays pertaining to said lines; trunk relays pertaining to said trunks; service conductors associated primarily with said trunks and passing through windings of trunk relays to contacts 80 of line relays; whereby the energization of trunk relays will result upon the energization of line relays; locking means on said trunk relays whereby the energization is continued in trunk relays energized primarily through line relay contacts and subsequent to the deenergization of such line relay; and means maintaining such locking dependently upon the continuance of current from the trunk to the connected line and through the substation telephone equipment upon that line; substantially as described.

38. In a telephone system, a group of lines; substation telephone equipments on said lines; a group of trunks; line relays pertaining to said lines; trunk relays pertaining to said trunks; service conductors associated primarily with said trunks and passing through windings of trunk relays to contacts of line relays, whereby the energization of trunk relays will result upon the energization of line relays; locking means whereby the armature contacts of the operated trunk relays are maintained closed 100 independently of the continuance of energization of the line relay primarily causing such closure; and means maintaining said locking dependently upon the continuance of current from the trunk of said relays to the connected line and through the substation telephone equipment upon that line, substantially as described.

39. In a telephone system, line conductors for speech current transmission; substation telephone equipments on said line conductors; line relays associated with said line conductors; trunk conductors for speech transmission; trunk relays associated with said trunk conductors; circuits whereby, by the energization of a line relay associated 110 with a specific line, relays associated with a trunk are energized and connect the speech current conductors of that trunk with the

speech current conductors of that specific line; locking means maintaining closed the contacts of such energized trunk relays independently of the continuance of energization of said action-initiating line relay; and means maintaining said locking independently upon the continuance of current from said trunk to the connected line and through the substation telephone equipment upon that line; substantially as described.

40. In a telephone system, a line having a pair of speech current conductors; a line relay associated with said line; a trunk having a pair of speech current conductors; trunk relays of two classes associated therewith; auxiliary speech-current-conductor trunk branches connecting contacts of the first class of trunk relays to the contacts of the second class of trunk relays; said trunk conductors terminating in the contacts of one class of relays and said line having extension conductors terminating in contacts in the other class of said relays; and circuits whereby a calling line energizing its line relay will, as a result thereof, energize one trunk relay of each class, thereby connecting the conductors of said trunk through one of said auxiliary trunk branches to the extension conductors of said line, substantially as described.

30 41. In a telephone system, a line having a pair of speech current conductors; a line relay associated with said line; a trunk having a pair of speech current conductors; trunk relays of two classes associated therewith; auxiliary speech-current conductors connecting contacts of the first class of trunk relays to contacts of the second class of trunk relays; said trunk conductors terminating in the contacts of one class of relays and said line having extension conductors terminating in contacts in the other class of said relays; circuits whereby a calling line energizing its line relay will, as a result thereof, energize one trunk relay of each class, thereby connecting the conductors of said trunk to said auxiliary conductors and thence to the extension conductors of said line; and means for locking the connections thus set up in said trunk relays to maintain those connections independently of the continuance of energization of the line relay originally energized, substantially as described.

55 42. In a telephone system, a line having a pair of speech current conductors with a telephone substation equipment connected thereon; a line relay associated with said line; a trunk having a pair of speech conductors; trunk relays of two classes associated therewith; auxiliary conductors connecting contacts of the first class of trunk relays to the contacts of the second class of trunk relays; said trunk conductors terminating in the contacts of one class of relays and said line having extension conductors terminat-

ing in contacts in the other class of said relays; circuits whereby a calling line energizing its line relay will, as a result thereof, energize one trunk relay of each class, thereby connecting the conductors of said trunk to a pair of said auxiliary conductors and connecting that pair of auxiliary conductors to the extension conductors of said line; means for locking the connections thus set up in said trunk relays to maintain those connections independently of the continuance of energization of the line relay originally energized; and circuits and devices maintaining said locking means independently upon the continuation of flow of current through said trunk and said line and substation equipment, substantially as described.

43. In a telephone system a group of lines numbered in tens and units; a line relay for each line; each of said line relays being adapted to close two current paths when energized; a trunk having a tens relay for each group of tens numbers in said line group and having a units relay for each group of units numbers in said line group; and circuits from the windings of said trunk relays from each tens relay to the contacts of all the line relays of lines in its tens group and from each units relay to the contacts of all line relays of lines in its units group, substantially as described.

44. In a telephone system, a group of lines numbered in tens and units; a line relay for each line, each of said line relays being adapted to close two current paths when energized; a trunk having a tens relay for each group of tens numbers in said line group and having a units relay for each group of units numbers in said line group; circuits from the windings of said trunk relays from each tens relay to the contacts of all the line relays of lines in its tens group and from the windings of each units relay to the contacts of all line relays in its units group, whereby, by the energization of any line relay resulting from the institution of a call upon its line, the tens trunk corresponding to the tens digit of that line and the units trunk relay corresponding to the units digit of that line will be energized; and means for locking the connections thus set up in said trunk relays to maintain those connections independently of the continuance of energization of the line relay originally energized, substantially as described.

45. In a telephone system, a group of lines numbered in tens and units; a line relay for each line; each of said line relays being adapted to close two current paths when energized; a trunk having a tens relay for each group of tens numbers in said line group and having a units relay for each group of units numbers in said line group; circuits from the windings of said trunk

relays from each tens relay to the contacts of all the line relays of lines in its tens group and from each units relay to the contacts of all line relays of lines in its units group; extension line circuits from all the said lines to contacts in said tens relays of said trunk; terminals for each of said trunks in each of said units relays; auxiliary trunk circuits between the contacts of said units relays and the contacts of said tens relays and extending from each units relay to all of the tens relays and from each units relay terminating in every tens relay in contacts associated with the contacts in that tens relay of the line in that tens group which is also in the units group of that units relay, whereby, by the energization of a specific line relay and the resulting energization of the tens trunk relay pertaining to that line's tens group and of the units trunk relay pertaining to that line's units group, the closure in the contacts of these trunk relays will result in the connecting of the speech current conductors of said trunk through one of said auxiliary trunk to the extension conductors of that specific line, substantially as described.

46. In a telephone system, a group of lines numbered in tens and units; a line relay for each line; each of said line relays being adapted to close two current paths when energized; a trunk having a tens relay for each group of tens numbers in said line group and having a units relay for each group of units numbers in said line group; circuits from the windings of said trunk relays from each tens relay to the contacts of all the line relays of lines in its tens group and from each units relay to the contacts of all the line relays of lines in its units group; extension line circuits from all the said lines to contacts in said tens relays of said trunk; terminals for said trunk in each of said units relays; auxiliary trunk circuits between the contacts of said units relays and the contacts of said tens relays and extending from each units relay to all of the tens relays and from each units relay terminating in every tens relay in contacts associated with the contacts in that tens relay of the line in that tens group which is also in the units group of that units relay, whereby, by the energization of a specific line relay and the resulting energization of the tens trunk relay pertaining to that line's tens group and of the units trunk relay pertaining to that line's units group, the closure in the contacts of those trunk relays will result in the connecting of the speech current conductors of said trunk through one of said auxiliary trunks to the extension conductors of that specific line; and means for locking the connections thus set up in said trunk relays to maintain those connections

independently of the continuance of energization of the line relay originally energized, substantially as described. 65

47. In a telephone system, lines; line extensions; trunks; relays pertaining to said trunks and divided into a plurality of classes, each trunk passing serially through contacts of all classes of said trunk relays; and circuits whereby a calling line will energize one relay in each of said classes and by so doing connect its line extension to one of 75 said trunks, substantially as described.

48. In a telephone system, lines, relays pertaining one to each of said lines; trunks; relays pertaining to each of said trunks and divided into a plurality of classes, each of 80 said trunks passing serially through contacts of all of said classes of trunk relays; circuits whereby the energization of a line relay, by the initiation of a call upon that line, will result in the energization of one 85 relay in each of said classes of trunk relays, and thus will result in the connection, through the contacts of said energized trunk relays, of the speech current conductors of the trunk to the speech current conductors 90 of the extension of the telephone line pertaining to the energized line relay; and locking circuits associated with said energized trunk relay and adapted to continue the energization of said trunk relays independently 95 of the continuance of energization of the line relay preliminarily controlling the trunk relays, substantially as described.

49. In a telephone system, lines, relays pertaining one to each of said lines; trunks 100 less in number than the number of lines, relays pertaining to each of said trunks and divided into a plurality of classes, each of said trunks passing serially to contacts of all of said classes of trunk relays; circuits 105 whereby the energization of a line relay, by the initiation of a call upon that line, will result in the energization of one relay in each of said classes of trunk relays, and thus will result in the connection, through the 110 contacts of said energized trunk relays, of the speech current conductors of the trunk to the speech current conductors of the extension of the telephone line pertaining to the energized line relay; and means for continuing the connection between the speech current conductors of the trunk and the speech current conductors of the line extension independently of the continuance 115 of the energization of the relay of that line, 120 substantially as described.

50. In a telephone system, a series of trunks; a relay in each of said trunks energized when said trunk is busy and deenergized when said trunk is idle; and a current supply circuit, passing first to the first trunk of said series, and passing thence through the contacts of said relay in that trunk, 125

when said relay is energized, to the second trunk of the series, and so on through the series until a trunk is encountered in which the said relay is not energized, said current supply circuit being continuous at all other points except the contacts of said controlling relays, substantially as described.

In testimony whereof I affix my signature in presence of two witnesses.

EDWARD E. CLEMENT.
